By Williams, Bradbury,
McCabe and Hauck, Atty's.

UNITED STATES PATENT OFFICE.

WALTER R. JORGENSEN, OF CHICAGO, ILLINOIS, ASSIGNOR TO POSTAM MANUFACTURING CO., A FIRM COMPOSED OF WALTER R. JORGENSEN, W. D. STANNARD, AND A. H. AMMANN, OF CHICAGO, ILLINOIS.

RECOIL DEVICE FOR GUNS.

Application filed June 19, 1925. Serial No. 38,147.

To all whom it may concern:

Be it known that I, WALTER R. JORGENSEN, a citizen of the United States, and resident of Chicago, in the county of Cook and State of Illinois, have invented certain new and useful Improvements in Recoil Devices for Guns, of which the following is a full, clear, concise, and exact description, reference being had to the accompanying drawings, forming a part of this specification.

My invention relates to a recoil device for guns, more particularly to a type of recoil device wherein the resilient cushioning element is carried by and within a leather garter adapted to be fitted around and laced snugly upon the rear end of a gun stock.

Among its objects my invention contemplates:

(a) A recoil device of the class mentioned, which is so constructed as to thoroughly protect the gun stock from injury by contact with the lace or eyelets through which the lace is passed.

(b) A recoil device of the type mentioned which is adapted snugly and neatly to be applied to gun stocks of various sizes.

(c) A recoil pad of the type mentioned which is of simple, economical and durable construction.

(d) A recoil device of the type mentioned, comprising a protecting flap which is applied thereto in a novel and effective way.

Other features, objects and advantages of my invention will appear from the following detailed description wherein reference is made to the accompanying drawings in which Figure 1 is a side elevational view illustrating my recoil device applied to a gun stock;

Figure 2 is a sectional view taken on the line 2-2 of Figure 3;

Figure 3 is a sectional view taken on the line 3-3 of Figure 2; and

Figure 4 is an enlarged fragmentary sectional view taken on the line 4-4 of Figure 1.

Similar characters of reference refer to similar parts throughout the several views.

In the drawings, reference character 5 indicates a gun stock, provided with a slightly curved rear end. This end, however, may be, and often is, straight. Lying against

the stock end 6, and held snugly there- 55
against, is a cushion 7 of sponge rubber which is retained in position by a garter 60
by and in which cushion is carried. The cushion is preferably of uniform thickness throughout and its front and rear faces correspond generally in shape with the stock end 6, against which the front face of the cushion bears.

Corresponding in size and shape with the rear face of the cushion 7 is a garter-back 65
8, preferably of relatively soft, pliable leather, this garter-back being firmly cemented to the rear face of the cushion 7 and being provided with an integral tongue 9 which is turned forwardly under the cushion 70
as is clearly indicated in Figure 3.

Adapted substantially to encircle the gun stock, and firmly cemented to cushion 7, with its rear edge lying immediately adjacent the margin of garter-back 8, is a garter-side 10, preferably of soft, pliable leather. The garter-side 10 is provided at the rear end of each of its opposed or proximal edges with an integral tongue 11. Each of the tongues 11-11 is turned under the cushion and the several tongues 9 and 11-11 are secured together by a rivet or a light 80
cutter indicated at 12.

Each of the opposed or proximal edges of the garter-side 10 is turned inwardly and back upon itself, as indicated at 13 and 14, and underlying the turned back portion 13 is a flap 15 of soft, pliable leather. Flap 15 is preferably cemented to the portions of the garter-side between which it is held and is also retained in position by the contiguous group of the metal eyelets 16, of which a plurality are carried by the garter-side at each of its opposed or proximal edges. 90

When the recoil device of my invention is operatively mounted upon a gun stock, as illustrated in the drawings, the flap 15 extends downwardly along the portion 13 of the garter-side, thence across the space between the proximal edges of the garter-side 100 and thence upwardly along the portion 14 of the garter-side to a line well above the plane of the eyelets 16. The garter is held firmly in position on the gun stock by lace 17 which is passed through the eyelets and back and forth across the gap between the proximal edges of the garter-side. 105

It will be understood, of course, that when

the gaiter is applied to a gun stock of substantial cross sectional area, the proximal edges of the gaiter-side may lie a substantial distance apart and that when the gaiter is applied to a smaller stock said proximal edges may abut. But in any event the flap 15 effectively prevents the gun stock from being scratched or abraded by either the lace 17 or the metal eyelets 16.

10 Having thus shown and described an illustrative embodiment of my invention, what I claim as new and desire to secure by Letters Patent of the United States is:

1. A recoil device for a gun stock which 15 consists of a gaiter including a resilient cushion of substantially uniform thickness corresponding generally in shape to the rear end of a gun stock, a gaiter-back cemented to the rear face of said cushion and provided at its lower end with a tongue, a gaiter-side adapted to extend around the gun stock and having its rear margin overlying and cemented to the edge of said cushion, tongues extending from the rear 25 ends of the proximal edges of said gaiter-side, said last mentioned tongues being turned toward each other under the cushion, said first mentioned tongue being turned forwardly under the cushion, means securing 30 the several tongues together, the material at each of the proximal edges of said gaiter-side being turned inwardly and back upon itself, a plurality of eyelets carried by each of the proximal edges of the gaiter-side, a lace co-operating with the eyelets to hold the gaiter on a gun stock, and a relatively wide flap having one of its margins held under one of the turned back portions 35 of the gaiter-side, said flap being adapted to bridge the gap between the proximal edges of the gaiter-side and to underlie the lace and the several eyelets.

2. A recoil device for a gun stock comprising a resilient cushion and a gaiter 45 wherein the cushion is mounted, said gaiter comprising a side member cemented to the cushion adapted to pass around a gun stock, the material at each of the proximal edges of said gaiter-side being turned inwardly

and back upon itself, a plurality of eyelets 50 extending through the gaiter-side near each of the proximal edges, a lace co-operating with said eyelets to hold the gaiter and cushion on the gun stock, and a relatively wide flap having one of its edges held under one of the turned back portions of the 55 gaiter-side, said flap being adapted to bridge the gap between the proximal edges of the gaiter-side and to underlie the lace and the several eyelets.

3. A recoil device for a gun stock comprising a resilient cushion and a gaiter wherein the cushion is carried, said gaiter comprising a side member adapted to extend around the gun stock and having the material at one of its proximal edges turned inwardly and backwardly upon itself, a plurality of eyelets extending through the gaiter-side near each of its proximal edges, a lace co-operating with said eyelets to hold 65 the gaiter in position, and a flexible flap having one of its edges held under the said turned back portion of the gaiter-side, said flap being adapted to bridge the space between the proximal edges of the gaiter-side and 70 to underlie the lace and the several eyelets.

4. A recoil device for gun stocks comprising a resilient cushion, a gaiter-back cemented to the rear face of said cushion, a gaiter-side adapted to lie around a gun 80 stock and having its rear margin cemented to the edge of said cushion, a forwardly turned tongue carried by said gaiter-back at its lower portion, tongues carried by the rear portions of the proximal edges of said gaiter-side, said tongues being superposed and secured each to the others, eyelets carried by the gaiter-side adjacent to its proximal edges, a lace co-operating with said eyelets to draw the proximal edges of the gaiter-side toward each other, and a flap carried by the gaiter-side adapted to bridge the space between the proximal edges of the gaiter-side and to underlie the lace.

In witness whereof, I hereunto subscribe 95 by name this 11th day of June, 1925.

WALTER R. JORGENSEN,
